GARMENT PROTECTOR

Edward H. Binns, Pittsburgh, Pa.

Application February 25, 1936. Serial No. 65,603

10. Claims. (Cl. 223—85)

This invention is an improvement in garment protectors adapted to cover the upper portion of the garment unit, such as a suit, coat, dress, cloak, or the like, when such wearing apparel is suspended from a coat hanger.

10 While the device is capable of being utilized in any environment, either domestic or commercial, it is particularly adapted for use in connection with a suspended series of garments arranged in a row or rows, for compact storage and exposure, as in a store.

It is so designed as to cover the upper portion of the goods, leaving the main portion exposed for inspection and selection, although such inspection is further facilitated by using transparent or semi-transparent material.

Generally stated, the protector is in the form of an inverted enclosing bag or pouch suspended over a hanger having an elongated supporting stem, and provided at its top with a perforated resilient disk section embracing the stem, for supporting engagement therewith at varying heights thereon. Two preferred embodiments of the invention are illustrated in the accompanying drawings, in which:

Fig. 1 is a face view of the invention suspended over a garment and hanger, in lowered position;

Fig. 2 is a similar view, showing the device elevated for removal of the garment;

30 Fig. 3 is a vertical section on the line III—III of Fig. 2;

Fig. 4 is an enlarged partial sectional view further illustrating the construction; Fig. 5 is a face view of the resilient friction disk element; Fig. 6 is a vertical section therethrough on the line VI—VI of Fig. 5.

Fig. 7 is a cross section on the line VII—VII of Fig. 1.

Fig. 8 is a view like Fig. 1 showing a modified construction;

Fig. 9 shows a plurality of such protectors suspended side by side.

Fig. 10 is an inner face view showing the annular securing means for the friction disk.

The protector A consists of a double-sided normally flat, comparatively shallow, inverted bag

50 mally flat comparatively shallow inverted bag, formed of a front 2 and corresponding back 3. The meeting edges are connected in any suitable manner, as by a strip 4, cemented or otherwise secured extending around the entire rounded or arched top and sides, leaving the bottom edges 5 apart for full opening in applying downwardly or removal upwardly.

55 The bottom edges are preferably reinforced by

(CL 222-85)

turning the material inwardly and upwardly on itself and securing them to the inner face of the front and back in any suitable manner as by cementing or adhesion, as at $\mathfrak{f}$.

The protector as thus made is adapted to be supported on the elongated stem 7 of a hanger 8 in covering relation with the upper portion of a garment carried by the hanger, when in lowered position as indicated in dotted lines, Fig. 1.

Also to be raised on the stem for elevation and support above the same, as in Fig. 2. Such manipulation and adjustment is accomplished by providing at the middle top portion of the protector, at its front or back, the supporting friction member 9. Such member consists of a disk or otherwise shaped comparatively small section of sheet rubber, or other resilient or elastic material. For the purpose of making elastic gripping clearance and frictional engagement with stem 7 disk 9 is vertically slotted at its middle, as indicated at 10 in Fig. 5, such slotted opening, at least of the diameter of stem 7, extending of course entirely through the protector wall 2. Disk 9 may be held in place by any suitable means as a retaining annulus 11 of thin material secured to the inner face of the protector wall and the outer edge of the disk.

The friction member 9 is located as nearly as possible to the middle top portion of the protector so that when mounted on stem 7 the supported hanger is approximately midway between the front 2 and back 3. Such arrangement is easily facilitated by the flexible nature of the protector itself, so as to assume its covering enclosure of the upper portion of the suspended goods. Friction member 9 is securely held in place between outer wall 2 and the inner covering 11 cemented or gummed together and to the rubber disk. 30 35

As thus constructed the resiliency of the disk 9 by its elastic grip upon the stem 1 reacts forcibly so as to frictionally resist lowering tendency of the comparatively light weight of the protector A. 40

It may be easily pushed up along the stem for clearance as in Fig. 2 or as easily lowered as in Fig. 1 by slight manual force, and will remain indefinitely where placed by friction.

I show in Fig. 8 a modified form of construction in which supplemental side extensions 13 extend downwardly from opposite lower corner portions of the main article, forming continuations thereof. Extensions 13 are rounded in conformity with the main rounded edges, as in the cross 55

section Fig. 7, and depend at each side materially below the middle, as shown.

The middle depth of the protector is substantially the same as in the principal figures, and the concaved edges 14 at front and back conform approximately to the general upper outline of the suspended garment. Thus when a protector of the form shown in Fig. 8 is lowered its depending side extensions 13 embrace and cover the shoulders and a considerable portion of the sleeves, providing corresponding additional protective covering, as indicated. In the same manner when the device is raised and supported on its stem, the entire garment is left exposed and may be easily removed from or replaced on the hanger, without interference, followed by lowering as described.

In turning up the lower edge portions 14 of the front and back on the arched outline their adhesive attachment to the inner sides may be facilitated by slitting the same at intervals, as indicated at 15.

The extensions 13 thus serve to protect the sleeves or side portions of suspended garments from rubbing contact with any adjacent surface, thus more completely ensuring protective coverage, and leave an open space between them for free access.

While any suitable material may be employed in making the protector, I preferably utilize flexible sheet material for the advantage of its strength, lightness of weight and preferably having the quality of visibility.

The protector of either design is easily made of two corresponding members, front and back, and the edges are secured together and reinforced in any suitable manner, as by edge connecting strips 4 of the same or suitable material, as for instance adhesive tape.

40 The stem 7 may be introduced through the slotted opening of the friction member 9 in any suitable manner, as by first inserting the extremity of hook 12, or by providing separable connection by its lower end with the hanger 8.

45 As thus made and provided with the frictional holding device engaging the elongated stem 7 when assembled therewith, the construction and operation of the invention in use will be readily understood and appreciated.

50 Because of the frictional engagement between the upper portion of the protector and the elongated suspending rod, the protector when elevated will there remain indefinitely. Thus the garments may be removed and others replaced, or the hanger may be left without any supported garments indefinitely, until further used. During such interval the protector will remain in its raised position, ready for lowering when the hanger is again supplied with a garment.

55 It may be made in various designs, sizes, or otherwise varied to suit any particular application or use. While affording practically complete protection to garments for limited periods, as in merchandising operations, with ample facility for quick and easy adjustment, it is also well adapted to domestic use, as in closets, etc.

Changes or variations in detail construction may be made by the skilled mechanic or fabricator within the scope of the following claims.

70 What I claim is:

1. A garment protecting cover consisting of an open bottom pouch composed of a front and back section transversely connected centrally of its top and side portions having at the upper middle portion of one section a slopingly disposed slotted one

piece section of friction creating material adapted to frictionally engage the shank of a garment support.

2. A garment protecting cover consisting of an open bottom pouch composed of a front and back section transversely connected centrally of its top and side portions having at the upper middle portion of one section a slopingly disposed vertically slotted one piece section of sheet rubber adapted to frictionally engage the shank of a garment support.

3. A garment protecting cover consisting of an inverted open bottom pouch having at its upper middle portion a one piece resilient holding element having a transverse slit therein providing oppositely disposed opening and closing gripping edge portions adapted to slidably and frictionally engage the shank of a garment support.

4. In combination with a garment support having a shank longer than the depth of an associated cover, a garment protecting cover consisting of an inverted open bottom pouch having at its upper middle portion a slopingly disposed vertically slotted elastic friction creating element slidably engaging the shank of the garment support.

5. In combination with a garment support having a shank longer than the depth of an associated cover, a garment protecting cover consisting of an inverted open bottom pouch having at its upper middle portion a vertically slotted section of sheet rubber slidably and frictionally engaging the shank of the garment support.

6. In combination with a garment support having a shank longer than the depth of an associated cover, a garment protecting cover consisting of an inverted open bottom pouch of flexible material having at its upper middle portion an attached disk of sheet rubber provided with a vertically slotted constricted opening therethrough slidably and frictionally engaging the shank of the garment support by its engagement therewith.

7. In combination with a garment support having a shank longer than the depth of an associated cover, a garment protecting cover consisting of an inverted open bottom pouch of flexible material having at its upper middle portion a disk of sheet rubber provided with a vertically slotted constricted opening therethrough, said opening extending through the cover and engaging the shank, and a reinforcing and connecting backing element therefor secured to the disk and cover around said opening.

8. In combination with a garment support having a shank longer than the depth of an associated cover, a garment protecting cover consisting of an inverted open bottom pouch having at its upper middle portion an elastic friction creating element having a vertically slotted opening slidably engaging the shank of the garment support, and provided with supplemental opposite side depending extensions.

9. In combination with a garment support having a shank longer than the depth of an associated cover, a garment protecting cover consisting of an inverted open bottom pouch having at its upper middle portion an elastic friction creating element having a vertically slotted opening slidably engaging the shank of the garment support, and provided with supplemental opposite side depending arcuate extensions adapted to form edgewise protectors for a suspended garment.

10. In combination with a garment support

having a shank longer than the depth of an associated cover, a garment protecting cover consisting of an inverted open bottom pouch formed of oppositely located front and back portions of flexible sheet material having rounded or arched top and side edge portions, means securing the edges together, and a disk of sheet rubber in-

corporated with the upper middle portion of the cover having a vertically slitted constricted opening therethrough for frictional holding engagement with the supporting shank of the garment support.
